UNITED STATES PATENT OFFICE

115,638

DESIGN FOR A SUGAR BOWL OR SIMILAR ARTICLE

Marvin G. Yutzey, Moundsville, W. Va., assignor to Fostoria Glass Company, Moundsville, W. Va., a corporation of West Virginia

Application April 6, 1939, Serial No. 84,096

Term of patent 7 years

To all whom it may concern:

Be it known that I, Marvin G. Yutzey, a citizen of the United States of America and resident of Moundsville, county of Marshall, and State of West Virginia, have invented a new, original, and ornamental Design for a Sugar Bowl or Similar Article, of which the following is a specification, reference being had to the accompanying drawing, forming part thereof, in which—

Figure 1 is a side elevational view of a sugar bowl or similar article, showing my new design; and

I claim:

The ornamental design for a sugar bowl or similar article, substantially as shown.

MARVIN G. YUTZEY.
